UNITED STATES PATENT OFFICE.

JOHN A. ALEXANDER AND FRANK K. BERRY, OF BATTLE CREEK, MICHIGAN. ASSIGNEES TO A. B. STOVE COMPANY, OF BATTLE CREEK, MICHIGAN, A CORPORATION OF MICHIGAN.

GAS RANGE.

1,070,097.

Specification of Letters Patent. Patented Aug. 12, 1913.

Application filed June 16, 1911. Serial No. 633,602.

To all whom it may concern:

Be it known that we, JOHN A. ALEXANDER and FRANK K. BERRY, citizens of the United States of America, residing at Battle Creek, 5 in the county of Calhoun and State of Michigan, have invented certain new and useful Improvements in Gas-Ranges, of which the following is a specification, reference being had therein to the accompanying drawings.

10 The invention relates to gas ranges and consists in the novel construction, arrangement and combination of parts as herein-after set forth.

In the drawings, Figure 1 is a side elevation of the range, partly in section; Fig. 2 is a front elevation thereof, partly in section; and Fig. 3 is a cross section through the oven. Fig. 4 is a longitudinal, vertical section of the range.

20 In the construction of gas ranges, it is usual to provide an open top section having one or more burners and their gas connections, beneath which is arranged a drip or dust pan T removable for the purpose of 25 cleaning. With the present construction the main frame of the range is arranged substantially in the plane of this drip or dust pan but is extended beyond the area of the open top and also forms a support for the 30 oven. Thus as shown, A is the rectangular main frame which is supported upon legs, B arranged at the corners thereof.

C is the open top or grid frame support above the main frame, D are the burners, 35 and E the gas connections therefor.

F is the oven arranged on an extension of the frame A, having its bottom substantially in the plane of said frame and extending up therefrom the desired height.

40 As shown, an oven G is superposed upon the oven F and the two ovens are arranged above the frame with a burner H at the top of the lower oven operating for both, and also constituting the broiler and toaster.

45 By the arrangement just described, the ovens as well as the open top are arranged at a height which is convenient for access, while the frame A forms a common supporting base for both arranged substantially in

50 the plane of the drip pan. The lower oven F has its front inclined rearward so that the door I in closed position is inclined as shown. This provides a longer base for the lower oven while the upper oven is of sufficient capacity for most uses. The

upper oven is provided with a lining J with surrounding hot air flues and a door K hinged at the side. The lower oven is further provided with a burner L at its base.

M is a hood arranged above the open top 60 section adjacent to the ovens F and G. This hood is preferably flush with the top of the upper oven G and forms a flue connection between said oven and the chimney pipe. Thus as shown, the side of the oven adjacent 65 to this hood is provided with apertures N connecting with the flue space between the outer and inner linings of the oven and in the rear wall of the oven are apertures O which connect with a flue P extending laterally and coupling into the chimney flue Q. This chimney flue also connects with the space within the hood M, the result being that the heated air passing from the oven and through the flues thereof will divide, 70 75 a portion passing through the apertures N under the hood and thence into the chimney flue Q, and another portion passing through the rear apertures O and flue P into the chimney flue Q.

As has been stated a burner L is arranged beneath the lower oven F. The purpose of this is not to heat the oven chamber but for use in cooking food where it is desirable to prevent the escape of odors into the room. 85 Thus by placing the boiling or cooking utensil within the oven F the odors instead of escaping into the room will be drawn into a flue R which connects this oven with the chimney flue Q.

The burner L does not interfere with the space within the oven F as it is arranged below the same, and to protect the burner a detachable pan or housing S is arranged therebeneath.

90 What we claim as our invention is:

1. In a gas range, the combination with an open top section, of an oven arranged at one end thereof, a hood above said open top section adjacent to said oven, a chimney flue connection to said hood, and said oven having a flue discharging into said hood and connected thereby with said chimney flue connection.

2. In a gas range, the combination with an open top section, of an oven arranged at one end of said section, a hood above said open top section abutting against said oven, said oven having flues discharging at the side into said hood and also discharging in 110

the rear, a laterally extending flue covering the rear discharge, and a chimney flue connected with said laterally extending flue and also with said hood.

- 5   3. In a gas range, the combination with an open top section, of an oven arranged at one end thereof, a hood above said open top section adjacent to said oven, and a chimney flue connection to said hood, said oven having a plurality of flue discharge apertures

at the side adjacent said hood opening into the latter and connected thereby with the chimney flue.

In testimony whereof we affix our signatures in presence of two witnesses:

JOHN A. ALEXANDER.
FRANK K. BERRY.

Witnesses:

JAMES P. BARRY,
W. J. BELKNAP.
